UNITED STATES PATENT OFFICE.

JAMES ROBERT BURNSIDE, OF TULSA, OKLAHOMA.

COMPOSITE ROOFING.

Application filed June 22, 1923. Serial No. 647,082.

To all whom it may concern:

Be it known that I, JAMES ROBERT BURNSIDE, a citizen of the United States, and a resident of Tulsa, in the county of Tulsa and State of Oklahoma, have invented certain new and useful Improvements in Composite Roofings, of which the following is a specification.

This invention relates to an improvement 10 in composite roofings which are adapted to be built up as they are laid to produce a unitary and organized roofing structure that is strong, durable, waterproof and fireproof and comparatively light although embodying in its structure non-corrosive metal as 15 well as non-metallic elements.

Another object of the invention is to provide a roofing of this character having these 20 advantages and capacities and which is at the same time adapted to be produced at comparatively slight expense since the materials of which it is composed are ordinarily available and since its application 25 does not require the employment of extraordinary skill or science.

Other objects and advantages of the invention reside in certain novel features of the construction, combination and arrangement of parts which will be hereinafter more 30 fully described and particularly pointed out in the appended claims, reference being had to the accompanying drawings forming part of this specification, and in which:

Figure 1 is a fragmentary perspective 35 view illustrating the preferred embodiment of the invention;

Figure 2 is a view thereof in vertical section; and

Figure 3 is a view similar to Figure 2 40 but showing a slightly modified form of the invention.

Referring to the drawings wherein for the sake of illustration is shown the preferred embodiment of the invention, the number 45 10 designates the under-structure of the roof. The roofing constituting the present invention is applied to this under-structure and comprises a dry sheet 11 of paper or felt which serves as the base or under-sheet of the roofing and acts as a 50 cushioning between the roofing and the under-structure of the roof. On the dry sheet 11 a layer or coating 12 of a mixture of asbestos and asphalt is applied and thoroughly spread so as to uniformly cover the paper 11. A thin sheet of metallic lead or

zinc 13 is next applied on the coating or layer 12 and is in turn covered by a coating or layer 14 similar in composition to the layer 12. A sheet of metallic lead or 60 zinc 15 is next applied onto the coating or layer 14 and onto the sheet 15 a final outer coating 17 of tar, pitch or asphalt is applied. The coating 17 may comprise either tar, pitch or asphalt or a mixture of 65 such substances with asbestos. Wherever a coating or layer is stated as comprising a mixture of tar, pitch or asphalt and asbestos the mixture is preferably made up of 30% asbestos and 70% asphalt, tar or 70 pitch. It is to be understood also that while the invention is shown and described for the sake of simplicity in illustration as consisting simply of a plurality or series of superimposed sheets that in practice the 75 sheets employed are overlapped laterally and longitudinally in the manner widely practiced in similar roofing or tarring. While lead is preferably employed as the material making up the metallic sheets 13 80 and 15 zinc may also be employed as indicated since both lead and zinc have substantially the same properties, both metals being pliant, malleable and substantially 85 non-corrosive.

When the under-structure of the roof includes the usual roofing boards, such as shown in Figure 1 the dry sheet 11 of paper is preferably nailed to the roof of boards but where this understructure consists of concrete the dry sheet 11 of paper is cemented to the concrete by means of asphalt, pitch, tar or any other suitable substance.

It will thus be seen that in the embodiment of the invention shown in Figure 1 the roofing structure consists in general of a base or under-sheet of paper or felt which acts as a cushion and alternate sheets of metal such as zinc or lead and adhesive 100 waterproof and fireproof substance such as a mixture of asphalt, tar or pitch and asbestos and an outer coating of asphalt, tar or pitch or a mixture of the same with asbestos as may be found desirable.

In the form of the invention shown in Figure 3 the roofing structure is in all respects like that disclosed in Figures 1 and 2 except that the layers between the metallic sheets instead of consisting simply of a 110 mixture of asphalt, tar or pitch and asbestos is of composite construction, being

made up of spaced layers consisting of asphalt, tar or pitch and asbestos and an intermediate sheet of building paper or roofing paper or felt as shown in Figure 3 wherein the spaced layers are designated as 20 and 21 and intermediate sheets of paper are designated at 23. In all other respects the roofing structure shown in Figure 3 is like that shown in Figures 1 and 10 2, a similar undersheet 25 as well as similar metallic sheets 26 and 27 and a similar outer coating 28 being employed as before. It is to be understood that the asbestos tempers the tar, pitch and renders the same practically fireproof without impairing the water resisting properties of these substances nor detracting from their capacity for combining the elements of the roof into a unitary and organized structure. In this manner a composite roofing structure is provided which is strong and durable as well as waterproof and weatherproof and which is comparatively inexpensive in that its application requires only ordinary skill and in that the elements of which it is composed are widely manufactured and ordi-

narily available at a comparatively slight cost. It is to be understood that the asphalt, tar or pitch or the mixture of the same with asbestos are mopped on in the usual manner.

I claim:

1. A roof structure comprising a plurality of sheets of lead and layers of adhesive between the sheets of lead. 35

2. A roof structure comprising a plurality of sheets of pliant and malleable non-corrosive metal and layers of adhesive between the sheets of metal. 40

3. A roof structure comprising a plurality of sheets of pliant and malleable non-corrosive metal and layers of adhesive between the sheets of metal, each layer of adhesive including asphalt. 45

4. A roof structure comprising an undersheet of cushioning material, a plurality of sheets of lead, layers of adhesive between the sheets of lead, a layer of adhesive between the lowermost sheet of lead and the undersheet, and a coating applied to the uppermost sheet of lead. 50

JAMES ROBERT BURNSIDE.
